Primary Examiner — Vy N Koenig

(57) **CLAIM**

The ornamental design for a hair removal device as shown and described.

DESCRIPTION

FIG. 1 is a top, front and left side perspective view of a hair removal device showing my new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a top, front and left side perspective view showing the hair removal device in a state of use;

FIG. 10 is a top, front and left side perspective view showing the hair removal device in another state of use; and,

FIG. 11 is a top, front and left side perspective view showing the hair removal device in yet another state of use.

The broken lines in the drawings illustrate portions of the hair removal device and environmental subject matters which form no part of the claimed design.

1 Claim, 11 Drawing Sheets
